[57] CLAIM

The ornamental design for a cup shaped sole periphery, as shown and described.

DESCRIPTION

FIG. 1 is a bottom plan view of a cup shaped sole periphery showing my new design;

FIG. 2 is a side elevational view of one side of the cup shaped sole periphery shown in FIG. 1;

FIG. 3 is a side elevational view of the other side of the cup shaped sole periphery shown in FIG. 1; and

FIG. 4 is a front elevational view of the cup shaped sole periphery shown in FIG. 1. and

The dotted line showing of trapezoidal ends of treads shown in FIGS. 1, 2 and 4 are for illustration purposes only and form no part of the claimed design.

FIG. 1

FIG. 2

FIG. 4

FIG. 3
